CLAIM

The ornamental design for a baby stroller, as shown and described.

DESCRIPTION

FIG. 1 is a perspective view of a baby stroller showing our new design;

FIG. 2 is a left side elevational view thereof;

FIG. 3 is a front elevational view thereof;

FIG. 4 is rear elevational view thereof;

FIG. 5 is a top plan view thereof; and,

FIG. 6 is a bottom plan view thereof.

The right side of the stroller (not shown) is a mirror image of the left side shown in FIG. 4.
